TUYÈRE

James A. Drogue, Noblesville, Ind., assignor to
American Engineering Company, Philadelphia,
Pa., a corporation of Pennsylvania

Application January 29, 1932. Serial No. 589,729

3 Claims. (Cl. 110—44)

This invention relates to improvements in tuyères, and more particularly in tuyères of the type employed in multiple retort underfeed stokers, which tuyères are composed of a plurality of plates arranged in superimposed stepped relation and having provision for passage of air therebetween to the fuel-bed.

The principal object of the invention is to improve the structural and functional characteristics of tuyères of the stated type.

More specifically, an object of the invention is to provide an improved design of the tuyère plate which shall render it more durable and less liable in assembly to injury due to unequal expansion and contraction.

Another object of the invention is to provide a novel tuyère plate of the character set forth so designed as to avoid initial strains developing in the molding operation.

A still further object of the invention is to provide a tuyère plate wherein the anchoring means is so positioned as to afford a minimum of interference to the free flow of air through the tuyère and a normally uniform distribution of air to the discharge outlets.

Still another object of the invention is to provide a tuyère plate of the stated type wherein the anchoring means for the plate is so located as to be unaffected by partial deterioration in that portion of the plate exposed to the incandescent fuel.

A further object of the invention is to provide a tuyère plate having novel anchoring means more effectively immobilizing the individual plates in the assembly and tending to prevent warping of the plates in operation.

The foregoing and other desirable objects hereinafter appearing I accomplish by the novel construction illustrated in the attached drawing, in which:

Figure 1 is a bottom plan view of a tuyère plate made in accordance with my invention;

Fig. 2 is a rear end elevation of the plate;

Fig. 3 is a side elevation of the plate;

Fig. 4 is a fragmentary side elevational and sectional view of a tuyère illustrating the relative positions of the tuyère plates in assembly; and

Fig. 5 is a section on the line 5—5, Fig. 1.

With reference to the drawing, a tuyère made in accordance with my invention comprises a plurality of plates formed as shown in Figs. 1, 2 and 3 and assembled as illustrated in Fig. 4. Each of the plates comprises a substantially flat body portion 1, the forward or nose portion 2 of which, formed on an arc, is slightly depressed below the upper plane of the body. Depending from the under side of the nose portion 2 of the plate is a plurality of channel-forming ribs 3, the forward edges 4 of which are beveled rear-

wardly from the edge of the nose portion and the rearward edges 5 of which are beveled in the reverse direction, the ribs 3 terminating rearwardly of the depressed nose portion but well in advance of the rear edge of the plate. The ribs 3 form an uninterrupted series distributed around the nose portion and converge towards the center of the plate as clearly illustrated. At each side of the body portion and extending longitudinally thereof is a depending rib or flange 6 which at its forward edge terminates adjacent the terminal ribs of the series 3. The rear ends of these ribs 6 designated by the reference numeral 7 incline upwardly to the plane of the upper face of the body portion 1, the latter extending rearwardly of the rear edges of the ribs 6 as indicated at 8.

Depending from the underside of the body portion 1 well rearwardly of the inner ends of the ribs 3 and located on opposite sides of the longitudinal center line of the plate is a pair of hooked anchor lugs 9, these hooks facing forwardly of the plate as illustrated. Directly to the rear of each of the hooks 9 and extending completely through the body portion 1 is an opening 10, these openings lying in part within the extension 8 and being adapted in assembly to receive the hooks 9 of the immediately overlying plate, as illustrated in Fig. 4, whereby the plates are interlocked one with another.

In assembly, as shown in Fig. 4, the lower edges of the ribs of the series 3 and the side boundary ribs 6 bear upon the upper flat surface of the underlying plate, while the inclined rear edges of the ribs 6 bear upon the upper edges of the side walls of the tuyère box indicated in Fig. 4 by the reference numeral 11. Air fed to the said box is thus confined beneath the tuyère plates and escapes to the fuel-bed through the passages formed between the ribs 3, a substantially uniform distribution of the air around the entire nose portion of the individual plates being afforded. Preferably and as shown in Fig. 5, the ribs 3 are somewhat tapered toward their lower edges.

By the aforescribed construction, I obtain a material improvement over tuyères of like character as constructed prior to my invention. Heretofore it has been customary to employ as an anchoring means for the plates a single hook located on the longitudinal center line of the plate and in the nose portion of the latter. By employing two hooks located as described at opposite sides of the longitudinal center line and well rearwardly of the inner ends of the channel-forming ribs 3, I obtain a more even distribution of the mass of the plate, with the result that cracking due to uneven expansion and contraction in operation is largely prevented. This more uniform distribution of mass also relieves initial strains set up in the mold in the casting opera-

tion and affords a stronger and more durable tuyère plate. The location of the anchor hooks also materially reduces interference with the free flow of air to the air channels between the ribs 3, and gives a greater uniformity of air distribution through the tuyères to the fuel-bed. The anchor hooks 9 being located well to the rear of the nose portion of the plate are not affected by deterioration of that portion of the tuyère plate 0 which by reason of exposure to the incandescent fuel is more liable to deterioration than the other portions. A maximum useful life for the individual plates and the tuyère as a whole is thus afforded.

15 Another material improvement resides in the employment of two anchor elements disposed as described. The prior type of tuyères employing a single locking element on the longitudinal center line is subject to rocking and minor displacements due to inequalities in the castings or warping of the tuyère plates in operation. The present device rectifies this defect by providing an anchor at each side of the center line of the tuyère, which not only tends to prevent warping but also 25 precludes undesirable rocking and minor relative displacements of the plates.

It will be understood that there may be some modification as to the form and arrangement of the various elements of the plate described 30 above without departure from the essential features of the invention.

I claim:

1. A tuyère plate adapted for assembly with similar plates in superimposed stepped relation 35 to form an inclined tuyère, said plate having a plurality of locking elements disposed respectively at opposite sides of the longitudinal center

line of the plate in widely spaced relation, and having rearwardly of said elements apertures for reception of the locking elements of the immediately overlying plate.

2. A cast metal furnace tuyère plate adapted 80 for assembly with similar plates in superimposed relation to form a tuyère, said plate comprising a body portion, a plurality of air directing members provided in said plate, and a plurality of fastening means depending from the underside 85 of said body portion, said fastening means being adapted in assembly to engage the next lower tuyère plate to retain the same in proper position, said fastening means being positioned on said plate at widely spaced points and remote from 90 said members whereby the mass of said plate is substantially evenly distributed, thereby preventing uneven strains from being set up therein when subjected to the variable temperature conditions 95 of furnace operation.

3. A furnace tuyère plate adapted for assembly with similar plates in superimposed relation to form a tuyère, said tuyère plate comprising a body portion, a plurality of ridges provided thereon, and a plurality of fastening means depending 100 from the under side of said body portion, said fastening means being disposed on said plate in widely spaced relation and remote from the ridges thereon whereby the mass thereof is substantially evenly distributed over the plate so as 105 to prevent warping or cracking due to the varying temperature conditions of the plate when formed in the mold, and said fastening means being adapted in assembly to engage the next lower tuyère plate to retain the same in proper position. 110
